UNITED STATES PATENT OFFICE.

JAY B. RHODES, OF KALAMAZOO, MICHIGAN, ASSIGNOR TO WESTERN WHEELED SCRAPER COMPANY, OF AURORA, ILLINOIS, A CORPORATION OF ILLINOIS.

VALVE MECHANISM FOR DUMP CARS.

Application filed March 30, 1918. Serial No. 225,845.

To all whom it may concern:

Be it known that I, JAY B. RHODES, a citizen of the United States, and a resident of Kalamazoo, in the county of Kalamazoo 5 and State of Michigan, have invented certain new and useful Improvements in Valve Mechanism for Dump Cars, of which the following is a specification, reference being had to the accompanying drawings.

10 My invention relates to dump cars of the type in which the car bed is dumped and restored to operative position by means of compressed air, and it has particularly to do with the valve mechanism by which the 15 admission of compressed air to the dumping cylinders and its exhaustion therefrom is controlled. My present invention has more especially to do with valve mechanism in which the further admission of compressed 20 air to the dumping cylinders is cut off by the direct action of the pistons therein, as they approach the end of their operating stroke. A construction of this kind is shown and described in Letters Patent, No. 1,361,- 25 904, dated December 14, 1920, granted upon my application, and the object of my present invention is to provide certain improvements upon the construction shown and described in my said patent. The specific features of improvement which form the subject 30 matter of this application will more fully hereinafter appear.

In the accompanying drawings,—

Fig. 1 is a view partly in vertical section, 35 illustrating part of a dump car cylinder and piston and the valve mechanism associated therewith, the parts being shown in the position they occupy while air under pressure is being supplied to the cylinder and just before the valve mechanism operates to 40 cut off such air pressure;

Fig. 2 is a horizontal section on line 2—2 of Fig. 1;

Fig. 3 is a horizontal section on line 3—3 45 of Fig. 1;

Fig. 4 is a horizontal section on line 4—4 of Fig. 1; and

Fig. 5 is a perspective view showing the upper end of one member of the cut-off 50 valve.

Referring to the drawings, 6 indicates one of the dumping cylinders, two of which are usually employed, one at each side of the car near the longitudinal center thereof, as 55 shown for example in Letters Patent No.

1,103,314. 7 indicates the bottom of the cylinder, and 8 the head thereof, through which works a tubular plunger 9, to which is attached the piston head 10. The bottom 7 of the cylinder is provided with a duct 11 60 for the passage of air in the usual way, so that by the admission of compressed air to said cylinder, the piston 10 may be forced toward the head 8 to dump the car bed or to restore it to its normal position after it 65 has been dumped.

12 indicates a valve body, or casing, which is mounted upon the cylinder head 8, preferably near the margin thereof, and is secured thereto by bolts 13, as shown in Fig. 70 1. 14 indicates a main valve chamber in the casing 12, which is provided with a lateral passage 14^a, leading to an air pipe 15, through which air under pressure is supplied to said valve chamber. The pipe 15 is provided with a cock 16, similar to an ordinary stop-and-waste cock, interposed between the pipe 15 and a pipe 17 which connects with a train pipe in the usual way.

18 indicates an annular channel in the 80 upper portion of the main valve chamber 14, and 19 indicates a sleeve which fits closely in the main valve chamber 14 and forms a lining therefor. The sleeve 19 is provided with perforations 20 opposite the channel 18 85 to permit air to pass from the valve chamber 14 into said channel. 21 indicates a cut-off chamber which is parallel with the main valve chamber 14, and is connected therewith by a transverse passage 22 which connects 90 with the annular channel 18, as shown in Fig. 1. 23 indicates a plunger mounted in the main valve chamber 14 and extending through the lower end thereof to a seat 24 in the valve casing. Said seat extends 95 around an exhaust port 25, as shown in Fig. 1. At its lower end the plunger 23 carries a washer 26 to provide a tight closure at the valve seat 24, and at its upper end, said plunger carries a cupped leather washer 27 100 which fits closely in the sleeve 19. Immediately below the washer 27 the plunger 23 is provided with a peripheral flange 28 to take the upward thrust of a spring 29 mounted upon said plunger, and tending 105 to normally to move said plunger upward to a position where the washer 27 overlies the perforations 20, and therefore prevents the admission of air to the channel 18 and transverse passage 22. When in this position the 110

lower end of the plunger 23 is off the seat 24 and the exhaust port 25 is open. The upper end of the main valve chamber 14 is closed by screw plug 30 which carries a depending stop 31 arranged to overlie the upper end of the plunger 23 and limit its upward movement.

32 indicates a duct in the form of a transverse passage which connects intermediately with the cut-off chamber 21 and extends between the lower end of the main valve chamber 14 and the exhaust port 25. Said transverse passage connects at its outer end with the operating cylinder, the supply of compressed air to which is controlled by the valve mechanism. In the construction shown this connection is made by a pipe 33 which leads to the duct 11 at the lower end of the cylinder 6, as shown in Fig. 1.

34—35 indicate the upper and lower members of a plunger mounted in the cut-off chamber 21, as best shown in Fig. 1. The member 35 is provided with a tubular stem 36 which screws into the member 34, and the latter member is provided at its upper end with a marginal flange 37 which rests upon a shoulder 38 provided in the upper portion of the cut-off chamber on a level with the transverse passage 22. 39—40 indicate oppositely-disposed cupped leather washers which are mounted between the members 34—35 and fit closely in the bore of the cut-off chamber, as shown in Fig. 1. It will be noted that the parts being in the position shown in Fig. 1, the plunger composed of the members 34—35 occupies that portion of the cut-off chamber which lies between the transverse passages 22—32, and consequently compressed air admitted to the main valve chamber 14, may flow through the transverse passage 22, down through the stem 36 to the transverse passage 32, and then through pipe 33 to the cylinder 6 below the piston therein.

41 indicates a pin provided with a head 42 which rests in the lower portion of the cut-off chamber 21. Said pin passes through a vertical passage 43 in the cylinder head 8 and extends down into the cylinder in position to be engaged by the piston 10 shortly before it reaches the upper end of its stroke, so that as said piston completes its stroke, it will move said pin upward for a short distance. When the piston again descends, said pin will drop by gravity to its normal position. 44 indicates a plunger fitted in the lower portion of the cut-off chamber 21 and normally resting upon the head 42 of the pin 41. Said plunger is provided with a cupped leather washer 44^a which fits closely in the bore of the cut-off chamber, and its upper end is provided with a socket in which is fitted a plug 45 carrying at its upper end a leather washer 46. This leather washer is adapted to engage the lower face

of the member 35, which overlies it, and in the construction shown is normally held in contact therewith by a spring 47, disposed between the plug 45 and the plunger 44, as shown in Fig. 1. In said figure the plug 45 is shown down out of operative position, which is the position it occupies when air under pressure is passing through the stem 36 and the transverse passage 32 to the cylinder, since the pressure of the air then operates to move the plug 45 down out of contact with the member 35. When the pressure is cut off, however, the tension of the spring 47 at once moves said plug up into engagement with the member 35, thereby closing the lower end of the passage through the stem 36.

48 indicates a valve member in the form of a spider, which is mounted in the upper portion of the cut-off chamber 21 above the member 34, as shown in Fig. 1. Said spider is provided with a central boss 49 which is adapted to fit into a recess 50 in a plug or cap 51, screwed into the valve casing 12, over the cut-off chamber, forming a closure for the upper end of said chamber. A spring 52 is mounted upon the boss 49 and bears in the socket 50, as shown in Fig. 1. Thus the spring 52 holds the valve member 48 down yieldingly on its seat and provides a yielding stop which limits the upward movement of the plunger members 34—35. The valve member 48 is provided centrally with a washer, preferably of leather, which is adapted to seat over the upper end of the stem 36 when the members 34—35 are moved upward far enough, thereby closing said stem against inflow of compressed air from the passage 22 under certain conditions, as hereinafter explained.

The operation of the valve mechanism described is as follows: When the valve is not subjected to pressure from the train pipe, the plunger 23 will be in its uppermost position against the stop 31, and the perforations 20 will be closed by the packing 27; also the exhaust port 25 will be open and the several parts of the cut-off valve mechanism will be in the position shown in Fig. 1, except that the plug 45 will be in engagement with the member 35, and the member 34 will be in engagement with the valve member 48. Assuming that the cock 16 is opened to admit air under pressure from the train pipe, the pressure of the air in the main valve chamber 14 will move the plunger 23 down to the position shown in Fig. 1, thereby opening the perforations 20 and closing the exhaust port 25. This will permit air under pressure to pass through passage 22 to the upper portion of the cut-off chamber 21, above the member 34, which will thereby be forced downward out of engagement with the valve member 48. This will permit the air to pass down through the tubular stem 36 to passage 32.

through which it will flow to pipe 33, and thence to the lower portion of cylinder 6. The pressure of the air in the stem 36 at this time will move the plug 45 down off its seat, against the action of spring 47. The pressure of the air admitted to the cylinder 6 will move the piston 10 up until it strikes the lower end of the pin 41, which will be moved upward until the piston 10 reaches the upper end of its stroke. This upward movement of the pin 41 will lift the plunger 44 and plug 45 until its washer 46 is seated against the lower face of the plunger member 35, thereby closing the lower 15 end of the passage through tubular stem 36 and cutting off further supply of compressed air to the cylinder 6. The upward movement of the plunger 44 will also carry the plunger members 34-35 up in the cut-off 20 chamber until member 34 strikes the washer carried by the spider 48, thereby closing the upper end of the stem 36, the spring 52 being compressed to a greater or less extent by this operation. Thus both ends of the 25 passage through the stem 36 are closed, insuring the complete cutting off of further compressed air. The parts will remain in this condition, with the passage through the stem 36 closed at both ends, until the pressure 30 is released from the inlet side of the valve by the engineer in the cab, or by turning the cock 16 to exhausting position. Until this is done, the pressure in the cylinder 6 may be maintained, as the plunger 23 will 35 remain in position to close the exhaust port since the pressure in the main valve chamber and the connecting passages will remain substantially constant, owing to the action of valves 48 and 45 which prevent flow of air 40 in either direction. As soon as the pressure in the main valve chamber 14 is released, however, the spring 29 will move the plunger 23 up against the stop 31 and close the perforations 20, at the same time opening 45 the exhaust port 25. This will permit the air in the cylinder 6 to be exhausted through said exhaust port, and with the ensuing downward movement of the piston 10, the pin 41 and the plunger 44 will move down 50 to the position shown in Fig. 1 by gravity, aided by the action of springs 52 and 47. When the plunger 44 moves down as described, the plug 45 will be held up in engagement with the lower end of the member 55 35 by the action of the spring 47, and the member 34 will be held up in engagement with the member 48, so that the passage through the stem 36 will remain closed at both ends. The members 34, 35 and 45 will, 60 however, be moved down to the positions shown in Fig. 1 as soon as air under pressure is again admitted to the main valve chamber 14.

Although, as has been suggested, my improved valve mechanism is designed pri-

marily for use on dump cars, it may also be used for other purposes, and therefore I do not limit myself to using such valve on dump cars, and the claims hereinafter made should be construed accordingly.

70

What I claim as my invention, and desire to secure by Letters Patent, is,—

1. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, a plunger movable endwise in said cut-off chamber for cutting off the admission of air from said passage to said cut-off chamber, and a duct communicating with said exhaust port and with said cut-off chamber and leading to an operating cylinder.

75

2. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, endwise movable means for cutting off the admission of air from said passage to said cut-off chamber, a duct communicating with said exhaust port and with said cut-off chamber and leading to an operating cylinder, and means for cutting off communication between said duct and said cut-off chamber.

90

3. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, a plunger in said cut-off chamber, said plunger having a passage therethrough, means for cutting off the admission of air from said first-mentioned passage to the passage through said plunger, and a duct communicating with said exhaust port and with the opposite end of the passage through said plunger and leading to an operating cylinder.

95

4. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, a plunger in said cut-off chamber, said plunger having a passage therethrough, means for cutting off the admission of air from said first-mentioned passage to the passage through said plunger, a duct communicating with said exhaust port and with the opposite end of the passage through said plunger and leading to an operating cylinder, and means for

100

105

110

115

120

125

130

cutting off communication between said duct and the latter passage.

5. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, a plunger 10 in said cut-off chamber, said plunger having a passage therethrough, means for cutting off the admission of air from said first-mentioned passage to the passage through said plunger, a duct communicating with said exhaust port and with the opposite end of the passage through said plunger and leading to an operating cylinder, and a cut-off 15 device normally operating to cut off communication between said duct and the latter passage and movable out of operative position by air pressure.

6. A valve comprising a casing having a main valve chamber, a cut-off chamber and an exhaust port, a passage connecting said chambers, fluid pressure controlled means in said valve chamber for controlling the admission of air to said passage and for opening or closing said exhaust port, a plunger 20 in said cut-off chamber, said plunger having a passage therethrough, means for cutting off the admission of air from said first-mentioned passage to the passage through said plunger, a duct communicating with said exhaust port and with the opposite end of the passage through said plunger and leading to an operating cylinder, a cut-off device normally operating to cut off communication 25 between said duct and the latter passage and movable out of operative position by air pressure, and means whereby said cut-off device may be held in operative position notwithstanding such air pressure.

7. A valve comprising a casing having a main valve chamber, a cut-off chamber and an exhaust port, a passage connecting said chambers, fluid pressure controlled means in said valve chamber controlling the admission of air to said passage and for opening or closing said exhaust port, a plunger in said 30 cut-off chamber, said plunger having a passage therethrough, a valve member adapted to cooperate with said plunger to cut off the admission of air from said first-mentioned passage to the passage through said plunger, a duct communicating with said exhaust port and with the latter passage and leading to an operating cylinder, and means for holding 35 said valve member and said plunger in operative engagement with each other notwithstanding pressure in said first-mentioned passage.

8. A valve comprising a casing having a main valve chamber, a cut-off chamber and an exhaust port, a passage connecting said 40 chambers, fluid pressure controlled means in

said valve chamber for controlling the admission of air to said passage and for opening or closing said exhaust port, a plunger in said cut-off chamber, said plunger having a passage therethrough, a valve member 70 adapted to cooperate with said plunger to cut off the admission of air from said first-mentioned passage to the passage through said plunger, a duct communicating with said exhaust port and with the latter passage 75 and leading to an operating cylinder, a cut-off device for cutting off the latter passage from said duct, and means for holding said valve member and said cut-off device in operative relation to said plunger notwithstanding pressure in said first-mentioned passage.

9. A valve comprising a casing having a main valve chamber and a cut-off chamber, a passage connecting said chambers, means in said main valve chamber for opening and closing said passage, a tubular member in said cut-off chamber forming an air duct, a cut-off device movable into engagement with said tubular member to prevent the flow of air therethrough, and means whereby said cut-off device may be held in operative position against pressure in said main valve chamber.

10. A valve comprising a casing having a main valve chamber and a cut-off chamber, a passage connecting said chambers, a tubular plunger in said cut-off chamber and movable longitudinally therein, a valve member 90 adapted to cooperate with said plunger when the latter is moved longitudinally in one direction, and a cut-off device movable into engagement with said plunger to prevent the flow of air therethrough.

11. A valve comprising a casing having a main valve chamber and a cut-off chamber, a passage connecting said chambers, means in said main valve chamber for opening and closing said passage, a tubular plunger in 110 said cut-off chamber, a cut-off device movable into engagement with said tubular plunger, said cut-off device comprising a plunger, a plug carried thereby, and a spring for projecting said plug and normally holding it in operative engagement with said plunger.

12. A valve comprising a casing having a main valve chamber and cut-off chamber, a passage connecting said chambers, means in said main valve chamber for opening and closing said passage, a tubular plunger in said cut-off chamber, a cut-off device movable into engagement with said tubular plunger, said cut-off device comprising a 125 plunger, a plug carried thereby, a spring for projecting said plug and normally holding it in operative engagement with said plunger, and means whereby said cut-off device may be held in operative engagement 130

with said plunger against the pressure of air in said main valve chamber.

13. A valve comprising a casing having a main valve chamber and a cut-off chamber, 5 a passage connecting said chambers, means in said main valve chamber for opening and closing said passage, an endwise movable tubular plunger in said cut-off chamber, a cut-off device movable into engagement with said 10 tubular plunger, said cut-off device comprising a plunger, a plug carried thereby, a spring for projecting said plug and normally holding it in operative engagement with said plunger, means whereby said cut-off device may be held in operative engagement with said plunger against the pressure of air in said main valve chamber, and a valve member adapted to be engaged by 15 said tubular plunger by endwise movement thereof.

14. The combination with a cylinder and a piston operating therein, of a valve comprising a casing having a main valve chamber and a cut-off chamber, a passage connecting said chambers, means in said main valve chamber for opening and closing said 20 passage, an exhaust port, a duct connecting said cut-off chamber with said cylinder and with said exhaust port, a tubular plunger 25 in said cut-off chamber, a cut-off device comprising a plunger, a plug carried thereby, and a spring for projecting said plug and normally holding it in operative engagement with said tubular plunger, and means operated by movement of said piston for holding 30 said cut-off device in operative engagement with said tubular plunger against the pressure of air in said main valve chamber.

15. A valve comprising a casing having a 40 cut-off chamber and inlet and outlet passages communicating therewith, means for controlling the admission of compressed air to said inlet passage, an endwise movable plunger in said chamber having a longitudinally-extending passage for connecting 45 said inlet passage with said outlet passage, and means adapted to cooperate with said plunger to close the passage therethrough against the admission of fluid thereto from 50 said inlet passage.

16. A valve comprising a casing having a cut-off chamber and inlet and outlet passages communicating therewith, means for controlling the admission of compressed air 55 to said inlet passage, an endwise movable plunger in said chamber having a longitudinally-extending passage for connecting said inlet passage with said outlet passage, a valve member adapted to cooperate with 60 said plunger to close the passage therethrough against the admission of fluid thereto from said inlet passage, and means for moving said plunger into operative engagement with said valve member.

17. A valve comprising a casing having a

cut-off chamber and inlet and outlet passages communicating therewith, means for controlling the admission of compressed air to said inlet passage, an endwise movable plunger in said chamber having a longitudinally-extending passage for connecting said inlet passage with said outlet passage, 70 a valve member adapted to cooperate with said plunger to close the passage therethrough against the admission of fluid thereto from said inlet passage, and fluid pressure operated means adapted to operate to hold said plunger in operative engagement with said valve member against the pressure of fluid in said inlet passage. 75

18. A valve comprising a casing having a cut-off chamber and inlet and outlet passages communicating therewith, means for controlling the admission of compressed air to said inlet passage, an endwise movable plunger in said chamber having a longitudinally-extending passage for connecting said inlet passage with said outlet passage, and means adapted to cooperate with said plunger to cut-off the passage therein from 80 said outlet passage.

19. A valve comprising a casing having a cut-off chamber and inlet and outlet passages communicating therewith, means for controlling the admission of compressed air to said inlet passage, an endwise movable plunger in said chamber having a longitudinally extending passage for connecting said inlet passage with said outlet passage, and fluid pressure operated means adapted 90 to operate to cut-off the passage in said plunger from said outlet passage.

20. A valve comprising a casing having a cut-off chamber and inlet and outlet passages communicating therewith, means for controlling the admission of compressed air to said inlet passage, a valve member in said chamber having a passage therethrough for connecting said inlet passage with said outlet passage, and devices cooperating with 100 said valve member to close both ends of the passage therethrough.

21. A valve comprising a casing having a cut-off chamber and inlet and outlet passages communicating therewith, means for controlling the admission of compressed air to said inlet passage, an endwise movable plunger in said chamber and having a longitudinally extending passage for connecting said inlet passage with said outlet passage, and devices adapted to cooperate with said plunger to close both ends of the passage 110 therethrough.

22. A valve comprising a casing having a cut-off chamber and inlet and outlet passages communicating therewith, means for controlling the admission of compressed air to said inlet passage, an endwise movable plunger in said chamber having a longitudinally-extending passage for connecting 120

- said inlet passage with said outlet passage, a valve member at the inlet end of the passage through said plunger and cooperating with said plunger to close said passage when 5 said plunger is moved longitudinally in one direction, a valve member cooperating with the outlet end of the passage through said plunger for closing the same, and means for moving said plunger and the latter valve 10 member to close both ends of the passage through the plunger against pressure in said inlet passage.
23. The combination with a cylinder and a piston operating therein, of a valve comprising a casing having a cut-off chamber and inlet and outlet passages communicating therewith, said outlet passage communicating with said cylinder, means for controlling the admission of compressed air to said inlet passage, an endwise movable plunger in 15 said chamber having a longitudinally-extending passage for connecting said inlet passage with said outlet passage, means adapted to cooperate with said plunger to 20 close the passage therethrough against the admission of fluid thereto from said inlet passage, and means operated by said piston for actuating said plunger to close the passage therethrough against the admission of fluid thereto from said inlet passage.
24. The combination with a cylinder and a piston operating therein, of a valve comprising a casing having a main valve chamber and a cut-off chamber, a passage connecting said chambers, means in said valve 25 chamber operated by air pressure to control the admission of air to said passage, a passage through said cut-off chamber adapted to communicate at one end with said first- 30 mentioned passage, a duct connecting the

opposite end of the passage through said cut-off chamber with said cylinder, and means operated by movement of said piston for closing the passage through said cut-off chamber at both ends. 45

25. The combination with a cylinder and a piston operating therein, of a valve comprising a casing having a main valve chamber and a cut-off chamber, a passage connecting said chambers, means in said valve chamber operated by air pressure to control the admission of air to said passage, a plunger in said cut-off chamber, said plunger having a passage therethrough adapted to communicate at one end with said first-mentioned passage, a duct communicating with the other end of the passage through said plunger and with said cylinder, and means operated by movement of said piston for cutting off communication between said first-mentioned passage and the passage through 50 said plunger. 55

26. The combination with a cylinder and a piston operating therein, of a valve comprising a casing having a main valve chamber and a cut-off chamber, a passage connecting said chambers, means in said valve chamber operated by air pressure to control the admission of air to said passage, a plunger in said cut-off chamber, said plunger having a passage therethrough adapted to communicate at one end with said first-mentioned passage, a duct communicating with the other end of the passage through said plunger and with said cylinder, and means 60 operated by the movement of the piston for closing the passage through said plunger at both ends. 65

JAY B. RHODES.
